Specification for Design.

Patented June 5, 1917.

Application filed March 23, 1916. Serial No. 86,320. Term of patent 14 years.

To all whom it may concern:

Be it known that I, GEORGE E. CURTISS, a citizen of the United States, and a resident of New Britain, in the county of Hartford, State of Connecticut, have invented a new, original, and ornamental Design for Handles for Forks or Similar Articles, of which the following is a specification, reference being had to the accompanying drawings, forming part hereof.

In the drawings—

Figure 1 is a front view of a handle for forks or similar articles embodying my new design.

Fig. 2 is a rear view.

Fig. 3 is a transverse sectional view on the line 3—3 of Fig. 1.

I claim—

The ornamental design for a handle for a fork or similar article.

GEORGE E. CURTISS.
